GUSTAV HARRY ANDERSSON, OF STOCKHOLM, SWEDEN, ASSIGNOR TO THE DE LAVAL
SEPARATOR COMPANY, OF NEW YORK, N. Y., A CORPORATION OF NEW YORK

PROCESS AND APPARATUS FOR SEPARATING LIQUIDS FROM SOLIDS

Application filed September 17, 1930, Serial No. 482,414, and in Sweden March 5, 1930.

In centrifuges for continuous separation and removal of solid matters from a liquid, or for continuous separation and removal of solid matters from liquids of different specific gravities which are themselves continuously separated and removed, it is known to introduce a flushing liquid into the bowl, preferably in the vicinity of the solids discharge, to facilitate the removal from the bowl of the solids or to reduce loss of the separated liquid constituent, or the heavier of the two separated constituents, of the original mixture.

The object of the invention is to automatically regulate the amount of flushing liquid supplied to the bowl to prevent or minimize outflow of separated liquid with the flushing liquid and solids, or admixture of flushing liquid with separated liquid, or both of these conditions, as may be desired.

The objects of the invention, as well as the way in which these objects are attained, will be made more clear in connection with the following description, in the course of which reference will be made to the devices for carrying out my new process illustrated in the drawings, in which—

Fig. 1 is a vertical sectional view of the centrifugal bowl which it is preferred to use in carrying out the process.

Figs. 2, 3, 4 and 5 are vertical sectional views, more or less diagrammatic, of different devices for regulating the inflow of flushing fluid relative to the outflow from the bowl of solids and liquid.

Fig. 6 is a vertical sectional view of a modified construction of centrifugal bowl.

In the centrifuge shown in Fig. 1 the mixture to be separated, which may be assumed to comprise two liquids of different specific gravities and solid matters (including sludges other than solids, of high specific gravities) is fed through the tube 1 into the central receiving chamber 2, whence it is conducted, through openings 3, into the separating chamber of the bowl. The bowl may contain a "liner" of frusto-conical discs 4 containing orifices aligning with opening 3, the entering mixture flowing up through the orifices in the conical discs and being thereby

distributed through the spaces between the discs. The lighter liquid moves toward the center of the bowl and discharges through an opening in the upper end of the neck of the top disc. The heavier liquid moves toward the periphery and outflows through a channel 6 between the top disc and the bowl wall and discharges through an opening at the upper end of the neck of the bowl. The solid matters collect in the sludge space 8 and slide along its outwardly inclined walls toward an opening or openings 10, through which they discharge.

The centrifuge, so far as described, illustrates a known type of centrifuge. It is open to certain serious objections. If the openings 10 are small, they will clog. If the openings are made sufficiently large to insure the discharge of all the solid matters, the escape, with the solid matters, of a very considerable proportion of the heavier separated liquid cannot be avoided.

It is known to introduce into the bowl either along with the mixture to be separated, or (much preferably) through an independent feed channel opening adjacent the periphery and preferably adjacent the openings 10, a flushing liquid or addition liquid to aid in expelling the solids through the openings 10. By this expedient, the openings may be made large enough to avoid clogging. See British patent to Aktiebolaget Separator et al., No. 10,314 of 1908. The expedient, however, is not operative, in most cases, to prevent the heavier liquid constituent of the original mixture from escaping with the solids and flushing liquid, or to prevent the admixture with and outflow of some of the flushing liquid with the separated heavier liquid constituent of the original mixture.

Instead of introducing the flushing liquid into the separating space of the bowl, it is introduced into a chamber or chambers outside of, and which may or may not entirely surround, the separating space of the bowl; said chamber communicating with the openings 10 and also having openings communicating with an outside receiving chamber. This broad conception is disclosed in an application filed by Hans Olof Lindgren September 100

18, 1930, Serial No. 482,659. It is also known to provide, around the periphery of the bowl, a number of small chambers which are provided with inner openings communicating with the separating or sludge space of the bowl and outer openings communicating with a stationary receiving chamber. Unless specifically claimed, these known sludge receiving and sludge discharging arrangements are to be considered equivalents of the concentric peripheral chamber 11 of Fig. 1. This specific chamber, which it is preferred to use, has outer walls which, in vertical cross-section, converge, from the outer openings 14, toward the sloping walls of the separating chamber. The flushing liquid is introduced through a fixed tube 12 and channel 13 into the chamber 11. The flushing liquid streams out with the solids through openings 14.

20 If the supply of flushing liquid through tube 12 is equal to the outflow through the openings 14, there will be no outflow of heavier separated liquid from the separating chamber of the bowl through the openings 10 and only the heavier solids will pass through these openings; and there will be no inflow of flushing liquid into the sludge space 8.

30 If it is of primary importance to prevent flushing liquid from streaming through openings 10 into sludge space 8 and therein becoming mixed with the heavier separated liquid, the volume of inflow of flushing liquid through tube 12 is maintained somewhat below the volume of outflow of flushing liquid and solids through openings 14, which results in a slight flow of separated liquid through openings 10 into chamber 11, sufficient to prevent inflow of flushing liquid through openings 10 into sludge space 8.

40 If it is of primary importance to prevent any loss of the separated heavier liquid, the volume of inflow of flushing liquid through tube 12 is maintained somewhat above the volume of outflow of flushing liquid and solids through openings 14, which results in a slight flow of flushing liquid through openings 10 into sludge space 8 sufficient to prevent outflow of the separated heavier liquid through openings 10 into chamber 11.

50 There are, however, various factors which make it difficult to predetermine with exactness the rate of inflow of flushing liquid required to insure against either, on the one hand, outflow of separated heavier liquid or, on the other hand, inflow of flushing liquid through openings 10. It is still more difficult to so nearly balance the inflow through tube 12 and the outflow through openings 14 as to substantially prevent any flow of either liquid through openings 10.

60 If, for example, the number of R. P. M. of the separator bowl is changed, or if the size of the outflow openings is changed, as, for example, if their size be increased by wear, the direction of liquid flow through openings 10

may be the reverse of that desired. Then again the percentage of solids in the liquid mixture and the rate at which the solids flow into the chamber 11 may vary, which may also result in an undesired reversal of flow and in an upsetting of the desired balance between inflow of flushing liquid to, and outflow of solids and liquid from, chamber 11.

70 An important object of the invention is to maintain such balance as may be desired between the inflow of flushing liquid to chamber 11 and the outflow therefrom of solids and liquids, including the maintenance, when desired, of substantial equality between such inflow and outflow so as to recover the solids substantially free of separated heavier liquid and recover the separated heavier liquid substantially free of flushing liquid.

75 Referring, first, to Fig. 2: The liquid streaming out through the openings 14 is collected and flows through a pipe line 15 into a container 17 provided with an outlet opening 16. Container 17 is provided with a float 18 the movements of which are transmitted, through a lever 19, to a valve 21 in the supply pipe 20, which connects with tube 12. With the flow through the tube 15 varies the level in the container 17 and the position of valve 21. By suitably constructing and adjusting valve 21, the relation between the quantities of liquid per time unit flowing through the outflow tube 15 and the inflow tube 20 may be maintained constant, or a predetermined excess of flow may be maintained through either pipe 15 or pipe 20.

80 It is assumed that the pressure in the supply pipe 20 ahead of the cock 21 is constant. If this be not the case and if it is difficult to provide a reduction valve before the valve 21, the supply may be regulated as shown in Fig. 3. A container 22, similar to container 17, is suspended from one end of a lever 23 turnable, between its ends, on a pin 24. Suspended from the other end of said lever is another similar container 25 whose bottom outlets connect with a pipe 26. The addition-liquid is supplied to the container 25 through pipe 27 and discharges through pipe 26 and tube 12 into the centrifuge. In the pipe 27 is a valve 28 which is connected, by a link 29 and an arm 30, with the lever 23.

85 If for any reason the quantity streaming out through the openings 14 in the wall of the centrifugal bowl increases, the level in the container 22 rises and the container 22 thereby becomes heavier and sinks. By means of the lever 23 and the link 29 the container acts on the valve 28 to more fully open it, thereby increasing the feed into the container 25 until equilibrium is brought about.

90 Still another way of effecting the desired automatic regulation is shown in Figure 4. The liquid streams out from the outlet openings 14 in the bowl through pipe 15, into

the container 32 wherein the level will vary with the rate of inflow of such liquid. As the float 33 in the container rises or falls, it raises or lowers respectively the movable part 34 of the supply pipe 35 for flushing liquid. From the part 34 the flushing liquid streams out into a supply container 36, and a float 37 therein regulates the supply from the part 34 in such way that the level in 10 the container follows the movements of the part 34 and thus also the variations of the level in the container 32. The outstream through the opening 38 will thus depend on the outstream through the openings 14 in 15 the centrifugal bowl. From the container 36 the flushing liquid is fed through a pipe line 39 and tube 12 into the centrifugal bowl. The conjunction between the amount of flushing liquid fed into the centrifuge and the 20 amount of liquid streaming out through the openings 14 can be regulated by means, for instance, of a valve in the discharge opening 38.

It is not necessary that the movable part 25 34 shall be connected with the other part 35 of the supply pipe by means of a hose 40, as shown in Fig. 4. Fig. 5 shows an alternative arrangement by means of which the same result may be obtained. The movable part 30 of the supply pipe 41 comprises a tube 42 movably arranged in the supply pipe and connected with the float 33 in the container 32 by means of an arm 43 and a rod 44.

In all the arrangements hereinbefore described, which are merely illustrative of many possible embodiments of my invention, the regulating devices are controlled by variations in the quantity of liquid in the container in which the liquid is collected 40 when it streams out from the centrifugal bowl, but variations in the specific gravity of such liquid can be utilized to effect the desired regulation. If the specific gravity of the separated liquid is different from that 45 of the flushing liquid, the specific gravity of the liquid in the container is changed if a quantity of such heavier separated liquid enters the chamber 11 through the holes 10 and is mixed with the flushing liquid. 50 This change in the specific gravity of the liquid in the container can be utilized for rendering the regulating device operative.

The centrifugal bowl herein described is intended for separation of solids from a 55 mixture of liquids, but the regulating device according to the present invention can, of course, also be used in connection with centrifuges intended for the separation of solids from a homogeneous liquid.

60 In Fig. 6 the chamber 11 of the separator bowl is shown as provided with adjustable outlets 50 for the flushing liquid. These outlets may be arranged as level outlets, the edges of which nearer the rotation center of 65 the bowl being adjustable in a radial direc-

tion. If the outlets are moved toward the rotation center the pressure of the liquid at the openings 10 and 14 increases. If the outlets are moved outward the opposite effect is produced. It is desirable to avoid loss of 70 liquid by outflow through outlets 50, and to provide a stationary ring of liquid the inner level of which is limited by the outlets.

To substantially prevent this outflow, or 75 limit it to a minimum, the liquid discharged through outlets 14 is carried, as above described, through pipe 15 into the container 17 of Fig. 2; while any flushing liquid discharging through outlets 50 is fed to the same 80 container through another pipe 51. Alternatively, the liquid from outlets 14 and 15 may be collected in a common receiving vessel and conveyed through a pipe (15 or 51) to container 17. The quantity of flushing liquid introduced into the bowl with this arrangement is determined not merely by the 85 amount of liquid discharged through outlets 14, but, in addition thereto, by the amount of liquid escaping through outlets 50.

The liquid escaping throughout outlets 50 90 may also be conveyed to the container 22 of Fig. 3, or to the containers 32 of Figs. 4 and 5; and any of the arrangements of Figs. 3, 4 or 5 will function in the manner hereinbefore described, with the additional advantage of minimizing loss of liquid.

What I claim is:

1. The process of separating liquids from solid matters which comprises subjecting a mixture thereof to centrifugal force and effecting a substantial separation of the liquid from the solids and separately outflowing the separated constituents, conveying a flushing liquid to the locus of centrifugal force and discharging it with the separated solids, and regulating the rate of supply of flushing liquid in accordance with the rate of outflow of the flushing liquid and solids from the locus of centrifugal force.

2. The process of separating liquids from solid matters which comprises subjecting a mixture thereof to centrifugal force and effecting a substantial separation of the liquid from the solids, separately discharging the separated liquid from the locus of separation, separately discharging the separated solid matters from the locus of separation while maintaining them under centrifugal force, conveying a flushing liquid to the locus of the separated solid matters, discharging the flushing liquid and separated solid matters from the locus of separated solid matters, and regulating the rate of supply of flushing liquid to the locus of separated solid matters in accordance with the rate of outflow therefrom.

3. A centrifugal apparatus comprising a rotatable bowl having an inlet for a mixture to be separated, an outlet for separated liquid,

and a peripheral sludge outlet, of a conduit for supplying flushing liquid to the vicinity of said sludge outlet, and means controlled by the rate of discharge from said outlet to regulate the rate of supply of flushing liquid.

4. A centrifugal apparatus comprising a rotatable bowl having an inlet for a mixture to be separated, an outlet for separated liquid, and a sludge-receiving peripheral space having inner openings communicating with the interior of the bowl and outer discharge openings, a conduit for supplying flushing liquid to said peripheral space, and means controlled by the rate of discharge through said peripheral space to regulate the rate of inflow of flushing liquid into said peripheral space.

5. A centrifugal apparatus comprising a rotatable bowl having an inlet for a mixture to be separated, an outlet for separated liquid, and a peripheral sludge outlet, of a conduit for supplying flushing liquid to the vicinity of said sludge outlet, a tank adapted to receive the discharge from the sludge outlet and provided with an outlet, a float in the tank, a conduit for supplying flushing liquid to the vicinity of said sludge outlet, and means controlled by said float to control the flow of flushing liquid into the bowl.

6. A centrifugal apparatus comprising a rotatable bowl having an inlet for a mixture to be separated, an outlet for separated liquid, and a sludge-receiving peripheral space having inner openings communicating with the interior of the bowl and outer discharge openings, a conduit for supplying flushing liquid to said peripheral space, a tank adapted to receive the discharge from the sludge outlet and provided with an outlet, a float in the tank, and means controlled by said float to control the flow of flushing liquid into said peripheral space.

In testimony of which invention, I have hereunto set my hand at Stockholm, Sweden, on this 29th day of August, 1930.

GUSTAV HARRY ANDERSSON.
